SHOE REPAIR FINISHING MACHINE

Soter Tavantzis, Detroit, Mich.

Application April 30, 1946; Serial No. 666,108

11 Claims. (Cl. 12—1)

1

This invention relates to shoe repairing machines and particularly to the arrangement and control of the operating parts thereof.

An important object of this invention is to provide a novel machine for repairing shoes which is compactly assembled to conserve space and is readily controllable to vary the operation of the moving parts thereof. Another important feature of the invention is to provide a novel unitary control mechanism for varying the speed of rotation of a pair of the shafts carrying the shoe repairing devices which occupies little space and is located in a position on the machine readily accessible to the operator. A further object of the invention is to provide a novel device for controlling the shaft speed which is also associated in a novel manner with the dust collector for automatically modifying the operation thereof in accordance with the control exercised by the device over the shaft speed.

Various other objects, advantages and meritorious features will become more fully apparent from the following specification, appended claims, and accompanying drawings wherein:

Fig. 1 is a front elevation of a machine embodying this invention.

Fig. 2 is a top plan view of the machine of Fig. 1.

Fig. 3 is a vertical cross sectional view along line 3—3 of Fig. 2.

Fig. 4 is an end view of the machine.

Fig. 5 is an enlarged cross sectional view along line 5—5 of Fig. 1.

Fig. 6 is an enlarged vertical sectional view through the control mechanism along line 6—6 of Fig. 6.

Fig. 7 is a view of the inside face of one of the members of the control mechanism showing the method of releasably locking the member in any one of a plurality of positions to which it may be adjusted, and.

Fig. 8 is an enlarged detail view of the valve control mechanism for the dust collector.

In the embodiment of the invention illustrated herein the machine comprises an elongated frame which, as best shown in Fig. 2, may be composed of two separate sections brought into end-to-end relation. Each section comprises vertical floor engaging corner frame members 10, spaced pairs of horizontal longitudinally extending members 12 and spaced horizontally extending transverse members 14. To conserve space, one section may be made narrower than the other as shown in Fig. 2. The two sections of the frame are usually mounted against a wall and the two part char-

2

acter of the frame enables one section to be adjusted transversely with respect to the other to accommodate the entire frame in the space allocated therefor in the shop in which the machine is installed. To facilitate this adjustment a flexible hose section 16 may be interposed in the blower pipe 18 which runs the length of the machine at the juncture of the two frame sections.

10 Each frame section supports a rotatable driven shaft on the front side thereof upon which is carried a series of shoe repairing devices of the character well known by those skilled in this art. One driven shaft is indicated at 20 on the left side of the machine illustrated herein and the other driven shaft is indicated at 22 on the right side thereof. Although these driven shafts may be arranged in end-to-end alignment it is preferred for the purpose of conserving space and 20 reducing the entire length of the machine to offset the two shafts and mount the shafts so that their adjacent ends overlap upon one another; as shown in Fig. 2. Having two separate driven shafts in lieu of one long shaft running 25 the length of the machine as heretofore it is possible to economize in the power used to drive these shafts by operating one when the shoe repair devices on the other shaft are not needed. The overlapping offset relation of the two shafts 30 enables the overall length of the machine to be reduced which is important in small shops where such machines are used.

A drive shaft 24 for rotating the two driven shafts is mounted on the rear side of one of the 35 frame sections, the left as shown in Fig. 2, in parallel relation to the driven shafts and with one end portion opposite the adjacent ends of the driven shafts. The drive shaft receives its motive power from an electric motor 26 located below the shaft by means of an endless belt 28 operatively extending between the two. Each driven shaft is operatively connected to the drive shaft by means of an endless belt. As shown in Figs. 2 and 5, the inner end portion of the 40 drive shaft opposite the adjacent ends of the driven shafts is provided with two driving pulley wheels 30 and 32. The driven shaft 20 is provided on its inner end with a driven pulley wheel 34 in alignment with the pulley wheel 30 on the drive shaft. The driven shaft 22 is likewise provided with a driven pulley wheel 36 on its inner end aligning with the pulley wheel 32 on the drive shaft. An endless belt 38 extends between the pulley wheels 30 and 34, a second endless belt 40 extends between the two pulley wheels

32 and 36. The two belts extend in slightly spaced apart parallel relation transversely of the machine as indicated in Figs. 1 and 2. For purpose of clarity the two endless belts 38 and 40 and the control mechanism therefor have been omitted from the end view of the machine in Fig. 4.

Interposed between the two endless belts at a height above the drive and driven shafts is a novel control mechanism for separately and independently controlling the drive relation between the shafts. This control mechanism is supported on a generally arched frame member 42 extending between the two inner corner posts 10—10 of the left frame section and resting thereon as shown in Fig. 5. This member is flanged along its outer edge and so shaped as to provide a flat horizontal section 44 upon which the control mechanism is mounted. The control mechanism comprises a fixed supporting member 46 preferably rounded on the top and the forward and rear sides and having laterally extending leg portions which are bolted or otherwise secured to the flat section 44. On either side of this fixed support are rotatable members 48 and 50. The latter are journaled to the fixed support by a single bearing member 52 (Figs. 6 and 7) extending through the support from one side to the other and projecting from the opposite sides to form the journals for the rotatable members. The rotatable members are preferably circular in formation and correspond in shape and formation to one another for interchangeable mounting and to the curvature of the fixed supports. From each rotatable member projects a handle for rotating the member. As shown, a handle 54 projects upwardly from member 48; a similar handle 56 projects upwardly from member 50.

Carried on the outer face of each rotatable member of the control mechanism in eccentric relation to its axis of rotation is an idling pulley wheel. The pulley wheel carried on the member 48 is designated by reference numeral 58; the pulley wheel on member 50 by reference numeral 60. These pulley wheels are disposed in the planes of the endless belts 38 and 40 and the latter are looped or passed over the pulley wheels in the manner illustrated in Fig. 5. The two extreme positions of the rotatable control members 48 and 50 are indicated by the dotted and full line positions of member 48 in Fig. 5. In dotted position, the pulley wheels provide sufficient slack in the endless belts which renders the drive shaft 24 ineffectual to rotate either of the driven shafts. When swung to their full line position as indicated in Fig. 5, the belts are sufficiently tight enough to rotate the driven at substantially the same rate of speed as the drive shaft.

The control mechanism is provided with novel means for releasably holding the rotatable members 48 and 50 and their respective handles in the two extreme positions and the several intermediate positions. This means comprises spring pressed detents or balls which engage the rotatable members and releasably lock the members in adjusted positions. Referring to Fig. 6, a novel provision is incorporated in the control mechanism which reduces the number of parts and economizes in the manufacture of the machine. A single aperture or bore 62 extends transversely of the fixed supporting member 46 and opens out on the opposite sides thereof. In each end of this bore is a detent member or ball 64. These balls are yieldingly urged outwardly by

a single coiled spring 66 which is common to both balls. The inner faces of the control members 48 and 50 are each provided with an arcuate series of depressions or recesses 68 as shown in Fig. 7, which as the members are rotated align successively with the axis of the bore. It is evident that as each depression appears opposite the end of the bore the balls 64 will seat therewith and releasably lock the control member in position. The intermediate positions of the control mechanism will provide variable speeds increasing as the handles are swung in the direction to apply more tension on the belts.

A shorter auxiliary driven shaft 70 is mounted on one of the frame sections, in this instance the wider section, for operating a special shoe repairing device 72. The device in the present embodiment of the invention is a shoe trimmer. A similar device 74 is mounted on the left end of the driven shaft 20 and the two trimmers as shown in Figs. 1 and 2 are disposed one above the other at the left end of the machine. Shaft 75 is driven by an endless belt 77 extending between the inner ends of the shafts and over pulleys mounted thereon. A dust or particle collecting hood 76 partially encloses the two trimmers. The blower pipe 18 previously referred to communicates at its remote end with the hood 76. The pipe 18 extends the length of the machine on substantially the level of the driven shafts, each part thereof in each frame section being joined together by the flexible hose section 16 previously described. The opposite end of the pipe 18 from the hood 76 communicates with a downwardly bent extension 78 which leads to the intake side of a blower 80. The latter is driven in any suitable way such as by an endless belt 82 operatively coupled to the driven shaft 22. The discharge end of the blower communicates with any suitable dust collecting receptacle such as the air pervious bag 84.

The auxiliary shaft 70 is driven by an endless belt 86 which as shown in Fig. 2 is passed over a pulley wheel 88 on the shaft 70 and a pulley wheel 90 in the drive shaft 24. Between these two pulleys and at a height thereabove is a control mechanism of the type previously described for varying the tension of the endless belt 86. This control mechanism includes a fixed supporting member 92 similar to support 46, a rotatable control member 94 similar to either control member 48 or 50 fixed to a rotatable stub shaft 95 and having a control handle 96, and an eccentric idling pulley wheel 98 similar to either pulley wheel 58 or 60 over which the belt 86 passes. A spring pressed detent similar to that previously described engages in recesses on the inner face of the rotatable member 94 to hold the same in any one of several positions of its movement. It is evident that swinging the handle 96 will vary the tension of the belt 86 and thereby vary the speed of the auxiliary shaft 70 from a zero speed to a speed sufficient to trim soles. The control mechanism for the belt is preferably mounted on a transverse arched support 100 having a flat top 102 on which the control mechanism is mounted. A similar arched support 104 is provided on the left end of the machine adjacent to the hood 76. The auxiliary shafts are 70 and 75 rotatably supported on the front side portions of these arched supports as indicated in Fig. 1.

At spaced intervals along the blower pipe 18 a plurality of dust collecting hoods or ducts 106 are provided which partially enclose certain of the

shoe repairing devices to exhaust the dust laden air therefrom. When the trimmers 72 and 74 are not in operation it is desirable to prevent the pipe 18 from exhausting air from the end hood 76 to more effectively operate the exhaust ducts 106. This is accomplished in a novel manner by automatically cutting off communication between the blower pipe 18 and the hood 76 when the control mechanism for the auxiliary shaft 70 is shifted to a position which reduces the speed of the shaft to zero. As shown in Fig. 3, a valve or gate member 108 is provided which is capable of swinging across the inlet opening 110 to the blower pipe 18. This gate member is pivoted at 112 to the inside wall of the hood 76 and in the full line position in Fig. 3 the gate is opened to permit the exhaust of air from the hood and in the dotted line position the gate member cuts off the opening 110. The gate member is provided with an extension 114 on the opposite side of pivotal connection to which is pivotally connected the end of a link 116. The latter has its opposite end pivotally connected through an arcuate slot 118 in the inner wall of the hood to a second link 120 on the outside of the hood which is pivotally supported intermediate its ends at 122 on the wall of the hood 76. The opposite end of the last mentioned link is pivotally connected to an arm 124 which extends upwardly for a short distance and then is jogged intermediate its ends as shown in Figs. 1 and 8 for fixed securement to the stub shaft 95 of the rotatable member 94 supported in the fixed member 92 of the control mechanism for the auxiliary driven shaft 70. The linkage connection is such that upon movement of the control member 94 by the handle 96 in the direction approaching maximum driving speed relation between the drive shaft 24 and the driven shaft 70 the gate member is swung to opened position, but when the control member is rotated in the opposite direction to slacken the belt drive the gate member is automatically swung to closed position. Thus when the auxiliary shaft 70 is inoperative the communication of the pipe 18 with the hood is cut off and the suction applied at the exhaust ducts 106 is thereby increased. When it is desired to use the trimmers 72 and 74, the shaft 22 is driven from the drive shaft 24 by moving lever 56 to one of its operative positions. Thus driven, the shaft 22 will operate the blower 80 by means of the belt 82 and cause air to be drawn from the hood 76 through the pipe 18.

The operation of the machine is readily apparent from the previous description. When the machine is set into operation the drive shaft 24 continuously rotates. The driven shafts 20, 22 and 70 may be independently coupled with the drive shaft by merely swinging any one or all the control handles 54, 56 and 96. The operator may adjust the speed of the driven shafts to any desired speed by releasably locking the control mechanisms at any one of the control positions provided. The control mechanisms are within easy reach of the operator and as shown herein are constructed of similarly shaped parts for lowering the cost of manufacture and for interchangeability.

Various standard shoe repair devices are carried by the driven shafts. In addition to the trimmers heretofore described, the driven shaft 20 may carry the brushes 130 and 132, the polishing wheels 134 and 136, a rougher 138 partially enclosed by an exhaust vent 106 and a wire brusher 140 on the extreme right. The last overlaps the inner end of the offset driven shaft 22.

Carried on the latter may be two sanders 142 and 144 which are partially enclosed by exhaust ducts 106, a pair of polishing wheels or sanders 146 and 148 and on the extreme right a heel scourer 150. The relation of these repair devices to one another and the overlapping relation of the two driven shafts 20 and 22 saves in the number of steps required by the operator to shift from one device to the other. The two part character of the frame and the independent operation of the driven shafts conserves space and economizes in the power consumed.

What I claim is:

1. A shoe repair machine comprising, in combination, a pair of rotatable shafts each having a length substantially one half that of the machine and each carrying shoe repair devices arranged thereon in axial spaced relationship, means mounting said shafts on the front side of the machine, one opposite each half section thereof, with the axes thereof in offset parallel relationship and with the adjacent ends of the shafts in overlapping relation, power means for rotating said shafts including a separate endless driving belt 25 operatively connecting the power means to each shaft, and control means for varying the tension of each of said endless driving belts for varying the rotation of said shafts and the devices carried thereon.

2. A shoe repair machine comprising, in combination, an elongated supporting structure, a pair of rotatably driven shafts each approximately equal to one half the length of the frame, shoe repairing appliances carried on each shaft 30 for rotation therewith, means mounting said shafts along one side of the supporting structure with one shaft occupying substantially one half the length of the supporting structure and the other shaft occupying the other half thereof with the axes of the shafts in parallel relation, a rotatable driving shaft, a pair of endless belts disposed transversely of the supporting structure midway between the ends thereof and operatively connecting said driving shaft to each of the adjacent ends of said driven shafts, and a control mechanism disposed between said endless belts 35 adapted to separately vary the tension of belts from a degree of tension which enables the driving shaft to rotate ineffectually to a degree of tension which enables the driving shaft to drive each of the driven shafts at substantially the same rate of speed.

3. A shoe repairing machine comprising, in combination, an elongated supporting structure 55 including a right frame section and a left frame section mounted in side by side relation but capable of bodily adjustment with respect to one another, a rotatable driven shaft mounted on the side of each frame section in parallel relation to one another and each carrying a series of axially spaced apart shoe repairing appliances, a rotatable driving shaft carried by the supporting structure in offset parallel relation to said driven shafts and overlapping the adjacent ends 60 thereof, a pair of axially spaced pulley wheels carried by said driving shaft, a pulley wheel carried on the adjacent end of each of said driven shafts aligning with one of the pulley wheels on the driving shaft, an endless belt operatively connecting each pulley on the driving shaft with the pulley on each driven shaft, said endless belts 65 extending in slightly spaced apart parallel relation and normally having sufficient slack so as to prevent the driving shaft from rotating either of said driven shafts; a control mechanism 70

carried by the supporting structure between said endless belts intermediate the driving and driven shafts including separate means for each endless belt for progressively increasing the tension thereof to proportionately increase the speed with which said driving shaft operates said driven shafts.

4. A shoe repair machine comprising, in combination, an elongated supporting structure, a pair of rotatable driven shafts each approximating in length about one half the length of the supporting structure and each carrying a series of axially spaced apart shoe repairing appliances, means mounting each shaft on the front side of the structure with one shaft occupying the left side thereof and the other shaft occupying the right side thereof, a rotatable driving shaft carried by the supporting structure in offset parallel relation to said driven shafts and overlapping the adjacent ends thereof, a pair of axially spaced pulley wheels carried by said driving shaft, a pulley wheel carried on the adjacent end of each of said driven shafts aligning with one of the pulley wheels on the driving shaft, an endless belt operatively connecting each pulley on the driving shaft with a pulley on each driven shaft, said endless belts extending in slightly spaced apart parallel relation and normally having sufficient slack so as to prevent the driving shaft from rotating either of said driven shafts, a control mechanism disposed between said endless belts intermediate the driving and driven shafts, said control mechanism including a pair of eccentrically mounted pulley wheels, one for each belt, positioned so that the belts pass over the rims thereof, manual control means for each eccentrically mounted pulley for bodily shifting the same about its eccentric axis of rotation for progressively increasing the tension of said belts to proportionately increase the speed at which said driving shaft rotates said driven shafts, and means for releasably holding either of said manual control means in any one of a plurality of positions.

5. A shoe repair machine comprising, in combination, a drive shaft, a pair of driven shafts, means mounting said driven shafts in parallel relation to said drive shaft, an endless belt for each of said driven shafts operatively connecting the drive shaft with each driven shaft, said endless belts extending in slightly spaced parallel relation to one another, a control mechanism for the endless belts interposed between said endless belts including a fixed support having a rotatable member journaled on either side thereof, a pulley wheel for each endless belt eccentrically carried on each of said rotatable members in position for its respective belt to pass thereover, a control handle on each of said rotatable members capable of rotating the same and swinging the pulley wheel carried thereon for varying the tension of the belt passing thereover, a movable lateral projecting member on either side of said support adapted to engage in any one of a series of seats provided in said rotatable members to releasably hold the same in adjusted position, and a single spring carried by said support yieldingly urging said lateral projecting members outwardly into engagement with said rotatable members.

6. A shoe repair machine comprising, in combination, a drive shaft, a pair of driven shafts, means mounting said driven shafts in parallel relation to said drive shaft, an endless belt for each of said driven shafts operatively connecting

the drive shaft with each driven shaft, said endless belts extending in slightly spaced parallel relation to one another, a control mechanism for the endless belts interposed between said endless belts including a fixed support having a rotatable member journaled on either side thereof, a pulley wheel for each endless belt eccentrically carried on each of said rotatable members in position for its respective belt to pass thereover, a control handle on each of said rotatable members capable of rotating the same and swinging the pulley wheel carried thereon for varying the tension of the belt passing thereover, said support having an aperture therethrough opening out on either side thereof, a single coiled spring disposed in said aperture having spring pressed elements on either end thereof projecting outwardly from the side of the support into engagement with said rotatable members, and said rotatable members having a series of depressions so positioned with respect to the elements that as the members are rotated by their respective handles the elements releasably seat within the depressions to hold the members in adjusted position.

7. A shoe repair machine comprising, in combination, a drive shaft, a pair of driven shafts each carrying a series of axially spaced shoe repairing devices thereon, means mounting said shafts in parallel overlapping relation to one another, an endless belt for each driven shaft extending in slightly spaced parallel relationship and operatively connecting the drive shaft with each driven shaft, a control mechanism for the endless belts located between the belts at a height above the drive and driven shafts, said control mechanism including a fixed support having a rotatable member journaled on either side thereof, a pulley wheel for each belt eccentrically carried on the outer faces of said rotatable members in position for its respective belt to pass thereover, a control handle projecting upwardly from each of said rotatable members adapted to rotate the same and swing the pulley wheel carried thereon through an arc which increases the tension of the belt from a slackened condition wherein the drive shaft is incapable of driving the driven shaft to a tensioned condition wherein the drive shaft rotates the driven shaft at substantially the same rate of speed, said rotatable members each having an arcuate series of recesses on their inner faces opposite the fixed support, said support having a bore therethrough opening out through the opposite sides thereof in alignment with said arcuate series of recesses, a locking element movably mounted in each end of said bore, and a single coiled spring in said bore between said locking elements yieldingly urging the elements outwardly into engagement with said recesses to releasably lock the rotatable members in adjusted position.

8. A shoe repair machine comprising, in combination, a frame, a drive shaft, a driven shaft carrying a series of axially spaced shoe repairing devices thereon, means mounting said shafts in parallel spaced apart relation on said frame, an endless belt extending between said drive and driven shafts operatively connecting the two together, a fixed member, a rotatable member journaled on said fixed member, a pulley wheel eccentrically journaled on said rotatable member in position for the endless belt to pass over the rim thereof, a control handle on said rotatable member adapted to rotate the same and swing said pulley wheel through an arc for varying the tension of the endless belt, and means

operatively interposed between said fixed member and said rotatable member for releasably holding the latter in any one of a plurality of positions.

9. A shoe repair machine comprising, in combination, a frame, a drive shaft, a driven shaft carrying a series of axially spaced shoe repairing devices thereon, means mounting said shafts in parallel spaced apart relation on said frame, an endless belt extending between said drive and driven shafts operatively connecting the two together, a fixed member, a rotatable member journaled on said fixed member, a pulley wheel eccentrically journaled on said rotatable member in position for the endless belt to pass over the rim thereof, a control handle on said rotatable member adapted to rotate the same and swing said pulley wheel through an arc for varying the tension of the endless belt, one of said members having an arcuate series of recesses on the face thereof opposite the other member, and an element carried by said other member yieldingly urged toward said series of recesses and engaging therein to releasably hold the rotatable member in any one of a plurality of positions it may be rotated by said control handle.

10. A shoe repair machine including, in combination, a drive shaft, a driven shaft carrying a shoe repairing device fixed therein for rotation therewith, an endless belt extending between said drive and driven shafts operatively connecting the two together, dust collecting means including a hood partially enclosing said shoe repair device and suction producing means communicating with the hood for withdrawing the particles created during the operation of the shoe repair device into the hood, a control mechanism for varying the tension of said endless belt and thereby vary the speed with which said drive shaft rotates said driven shaft, and means operatively connecting said control mechanism to said dust collecting means and operable to

vary the operation of the latter in response to the movements of the control mechanism.

11. A shoe repair device comprising, in combination, a frame, a drive shaft, a driven shaft having a shoe repair device fixed thereon for rotation therewith, means mounting said shafts on said frame in spaced parallel relation, an endless belt extending between said shafts operatively connecting the two together, dust collecting means carried by said frame including a hood partially enclosing said shoe repair device and suction producing means for communicating with the hood for withdrawing the particles created during the operation of the device into the hood, a valve member movable either to a position to cut off the communication between said suction producing means and said hood or to a position opening the communication therebetween, a control mechanism for varying the tension of said endless belt including an eccentrically mounted idling pulley wheel over the rim of which the belt passes, a handle for bodily moving the pulley wheel, and an operative connection between said handle and said valve member adapted to shift the latter to either one of said positions upon movement of the handle.
